FINGER RING

Robert N. Gibeault, 40 Hunting St.
North Attleboro, Mass.

Filed Mar. 21, 1960, Ser. No. 59,803

Term of patent 14 years

(Cl. D45—10)

Fig. 1

Fig. 2

Fig. 3

FIG. 1 is a front elevation of a finger ring embodying my new design;

FIG. 2 is a view in side elevation thereof; and,

FIG. 3 is a top plan view, thereof.

The essential features of my design reside in the portions shown in full lines.

I claim:

The ornamental design for a finger ring, substantially as shown and described.
